UNITED STATES PATENT OFFICE.

HENRY NIELSON, OF CLEVELAND, OHIO, ASSIGNOR TO THE OSBORN MANUFACTURING COMPANY, OF CLEVELAND, OHIO, A CORPORATION OF OHIO.

TOOL FOR BRUSH-MAKERS.

SPECIFICATION forming part of Letters Patent No. 759,465, dated May 10, 1904.

Application filed July 17, 1903. Serial No. 165,948. (No model.)

To all whom it may concern:

Be it known that I, HENRY NIELSON, a subject of the King of Denmark, and a resident of Cleveland, county of Cuyahoga, and State of Ohio, have invented a new and useful Improvement in Tools for Brush-Makers, of which the following is a specification, the principle of the invention being herein explained and the best mode in which I have contemplated applying 10 that principle, so as to distinguish it from other inventions.

My invention relates to tools for brush-makers, and particularly to such tools as are employed in fastening the bristles to the handle or back of the brush, its object being to provide an efficient and economical device for the purpose set forth.

The annexed drawings and the following description set forth in detail certain means 20 embodying the invention, such disclosed means constituting but one of various mechanical forms in which the principle of the invention may be used.

In said annexed drawings, Figure I represents a perspective view of a device embodying my invention with a wire used for fastening bristles contained therein, and Fig. II, represents a longitudinal sectional view of said device with the wire therein.

30 The device embodying my invention consists of a handle A, of copper or other suitable material, a long metallic needle B, one end of which is fastened in the handle A so as to extend out longitudinally from said handle, as shown in Fig. II, and a clamping-lever C, mounted upon said handle by means of a pin d running transversely through the latter and upon which pin said clamping-lever is oscillatory for a certain distance, as will be hereinafter explained. The handle A consists in the device illustrated of two semicylindrical pieces a' and a'', assembled by placing their flat surfaces so that they abut each other, thus forming a cylindrical handle, as shown. One 45 of said pieces a' is slotted vertically to receive the head c of the clamping-lever C, which head is fastened within the slot e by means of a pin d passing transversely through the piece a'

lateral of the slot. The bottom of the head c is provided with a cam or eccentric surface 50 c', which may be caused to intersect a passage-way a³, as hereinafter described. It is thus seen that the lever C has free play upon the pin d, which play is limited by the ends of the slot e and the eccentricity of the bottom of the head c. The flat surfaces of the semicylindrical pieces a' and a'' are furrowed, so as to form when said pieces are assembled a passage-way a³ through the handle A 55 through which a wire may be passed. The clamping-lever C is so fastened to the handle A that its head c exerts no pressure upon the wire when there is no pressure brought to bear upon the lever C. The needle B is pointed at its outer end to enable its easy passage 60 through the perforations in the handle of a brush and is also provided with a small eye b, through which the wire may be passed. Opposite said slot e is secured a flat piece D, of hard steel, having a serrated biting-surface 65 d'. 70

The operation of my device is as follows: The wire F is threaded from a spool or any other suitable source (not shown) through the passage-way a³ and the eye b. The pointed end 75 of the needle is then passed through a perforation in a brush back or handle, from rear to front of said back, and tufts of bristles are looped within that part of the wire projecting from the eye b in a manner well known to 80 those skilled in the art. The needle is then withdrawn from the perforation, bringing with it to the rear of the brush-back the bristle tufts, which are looped within the wire, the tension of the wire being maintained by holding down tight with the hand the lever c' of the clamping device C, whereby the head c bears down upon the wire F, clamps it upon the piece D, and prevents it from slipping. 85 The bristle tufts having been withdrawn to the rear of the brush-back, they are fastened and the needle is passed through another perforation of the brush-back, the pressure upon the lever c' having been relaxed, so as to enable the easy feed of the wire required. 90 A bristle tuft is again looped within the wire 95

and the process repeated, as hereinbefore described.

Other modes of applying the principle of my invention may be employed instead of the 5 one explained, change being made as regards the means herein disclosed, provided the means stated by the following claim or the equivalent of such stated means be employed.

I therefore particularly point out and distinctly claim as my invention—

In a tool for brush-makers, the combination of a handle, a recessed portion in said handle, a serrated member below said recess and running longitudinally of said recess and 15 handle, a guiding-needle for wire mounted in said handle, a passage-way for wire running

longitudinally of said handle and intermediate of said recess and said serrated member, and a manually-operated clamping-lever oscillatory mounted in said recess and provided 20 with an eccentric surface at its inner portion arranged to intersect said passage-way, whereby said eccentric surface and serrated member are adapted to hold the wire in said passage-way at one end of the lever's oscillatory stroke 25 and adapted to release said wire at the other, end of the stroke.

Signed by me this 14th day of July, 1903.
HENRY NIELSON.

Attest:

JOHN H. GALLOWAY,
W. H. MOULTON.
